UNITED STATES PATENT OFFICE.

HARLOW S. DEACON, OF PHILADELPHIA, PENNSYLVANIA.

SOUND-REPRODUCER.

1,332,661

Specification of Letters Patent.

Patented Mar. 2, 1920.

Application filed November 4, 1915. Serial No. 59,554.

To all whom it may concern:

Be it known that I, HARLOW S. DEACON, a citizen of the United States, and a resident of the city of Philadelphia, county of Philadelphia, and State of Pennsylvania, have invented certain new and useful Improvements in Sound-Reproducers, of which the following is a full, clear, and exact description.

10 There are today two distinct types of records for sound reproducing machines on the market, namely, that having a laterally undulatory groove in its surface, and that having in its surface a vertically undulatory 15 groove.

Ordinarily, machines designed to accommodate one of these kinds of records are provided with a sound reproducer peculiarly adapted to the specific type of record with 20 which it is intended to operate, and when it is desired to make the reproduction of either type of record possible upon a given machine, two separate reproducers are generally necessary and sometimes provided.

25 However, in the manufacture of low-priced machines the expense incident to providing two reproducers to each machine is prohibitive, and yet the owner of a talking machine does not wish to be restricted to the 30 use of records of only one of the above-mentioned types. Therefore, the reproducer hereinafter described has been perfected for the purpose of playing records of either type upon a machine so equipped.

35 Another object is to provide a reproducer or sound box of such construction that one type of record may replace a record of another type, and the reproduction of the one equal the reproduction of the other, without 40 altering the position of the sound box with respect to the machine proper.

45 And another object is to provide a stylus bar which is particularly well adapted for use in the improved reproducer, the same presenting a longitudinal central axis in the form of a continuous and regular curve from the stylus-receiving head to the point of attachment to the diaphragm.

50 Further objects and advantages of the invention are fully brought out in the following description, when read in conjunction with the accompanying drawings, in which Figure 1 is a side elevation of a sound box embodying the preferred form of the invention; Fig. 2 is an under side elevation in

line with the stylus; and Fig. 3 is a front elevation of the same.

Referring to the drawings, the illustrated embodiment of the invention comprises a casing 5 in which is positioned the usual diaphragm 6 by means of one or more gaskets 7. To the back of the said casing is secured a tubular coupling 8 for mounting the same upon the hollow tone arm of a talking machine (not shown), said casing and coupling being separated by a sound-insulating gasket 9.

To one peripheral edge portion of the sound box is a pair of integral shoulders or brackets 14 and 15, which in the case of a 70 reproducer formed by dies may comprise separate members secured to the casing proper in any suitable manner. Each of the said brackets is angularly directed at its extremity 16 and through that portion 75 thereof extend suitable bearing pinions 17, which in the present instance are suitably pointed screws with lock washers 18 for maintaining the former in a given position.

The bracket 15 is longer than the bracket 80 14, and in fact this is true to such an extent that the line of the pins 17 lies at an angle of about forty-five degrees with the plane of the casing 5. As a result of this arrangement the inner end portion 20 of the stylus 85 bar vibrates the diaphragm inwardly and outwardly, equally well if the impulses given to the stylus 21 are in a plane substantially parallel with, or at right angles to, that of the said diaphragm, or in the general 90 directions of the lines A and B.

While there is possibly some energy lost in the transformation of the undulatory vibrations of the record grooves in one direction to those of the stylus bar in another 95 direction, the angle of the transverse axis of oscillation of the stylus bar with respect to the plane of the diaphragm is made such that the reproduction of one type of record is equal to that of another type, and with a 100 very sensitive reproducer excellent results are obtained.

It is also to be noted that, as an aid to the attainment of this result, it has been found of particular advantage to construct the 105 stylus bar from the axis of oscillation to the point of attachment to the diaphragm in the form of a regular, three dimensional, or spiral curve with no sudden or sharp bends. This prevents local bending of the said 110

stylus bar and insures its oscillation as a substantially rigid member throughout its length.

Having thus described my invention, what I claim and desire to protect by Letters Patent of the United States is:

- 5 1. A sound reproducer, comprising a casing, a diaphragm carried by said casing, a stylus bar connected to said diaphragm, and a mounting for said stylus bar positioning the transverse axis of vibration of said bar, 20 when said reproducer is in normal operative position, at an acute angle with said casing, with said diaphragm, and with a disk record lying in its normal horizontal plane and from which sound is adapted to be reproduced by said reproducer.
- 10 10. a mounting for said stylus bar positioning the transverse axis of vibration of said bar, when said reproducer is in normal operative position, at an acute angle with said casing, with said diaphragm, and with a horizontal 25 plane.
- 15 15. plane.
2. A sound reproducer, comprising a cas-

ing, a diaphragm carried by said casing, a stylus bar connected to said diaphragm, and a mounting for said stylus bar positioning the transverse axis of vibration of said bar, 20 when said reproducer is in normal operative position, at an acute angle with said casing, with said diaphragm, and with a disk record lying in its normal horizontal plane and from which sound is adapted to be reproduced by said reproducer.

In witness whereof, I have hereunto set my hand this second day of November, 1915.

HARLOW S. DEACON.
